PHOTOELECTRIC SORTING APPARATUS

Willard H. Hickok, Bloomfield, N. J., assignor to
Radio Corporation of America, a corporation of
Delaware

Application October 31, 1940, Serial No. 363,668

6 Claims. (Cl. 209—111)

My invention relates to sorting apparatus and particularly to apparatus and machines capable of photoelectrically inspecting and sorting a number of objects simultaneously for defects in quality or color.

It is an object of my invention to provide a more rapid inspection of materials or objects and a selection of materials or objects in accordance with a predetermined standard of quality or color.

Another object is to provide low cost apparatus for selecting materials or objects in accordance with color variations of the objects; and it is a still further object to provide sorting apparatus with which the elemental areas of the materials or objects to be inspected may be sequentially analyzed for quality or color defects.

In accordance with my invention I move one or more objects to be examined or sorted under a narrow strip of light which is reflected upon a photoelectric tube having a number of charge storage electrodes and on which elemental area images of the objects to be examined are expanded in the direction of motion of the objects to produce electrostatic charges representative of the quality or color of the object images. The electrostatic charges are sequentially neutralized to produce a current flow which is simultaneously applied to one or more selecting mechanisms which are synchronized with the neutralization of the electrostatic charges. These and other objects, features, and advantages of my invention will be apparent when considered in view of the following description and the accompanying drawing in which:

Figure 1 is a perspective view of sorting apparatus made in accordance with my invention and incorporating a single photoelectric tube; Figure 2 is a perspective cross-sectional view of a portion of the electrode and, Figure 3 is a cross-section of a portion of the apparatus shown in Figure 1.

In accordance with my invention a number of objects to be examined and from which imperfect or off color objects are to be sorted are carried by an endless belt under a relatively narrow strip or beam of light extending transversely of the belt in its direction of motion. Elemental strip images of the objects to be sorted are projected upon a charge storage electrode comprising a number of segments preferably equal to the number of side-by-side objects on the endless belt. These images generate charges which are sequentially dissipated by an electron beam scanned across the electrode segments to generate

sequential current impulses which are applied in order of their occurrence to a plurality of discharge mechanisms arranged in the same order as the order in which the objects appear on the endless belt.

Referring to Figure 1, I will first describe the photoelectric tube used in combination with my sorting apparatus. The tube 1 comprises a highly evacuated glass envelope enclosing a conventional type electron gun and a flat target or mosaic electrode 2 symmetrically positioned in the envelope so that its front surface may be scanned by a beam of electrons from the electron gun and also may have projected upon it elemental optical images of the objects to be inspected. Since the images are produced by light from objects situated outside the tube, a portion of the tube such as the transparent window 3 is made optically uniform so the images may be projected upon the mosaic electrode 2 with a minimum of distortion.

The electron gun assembly 4 comprises an electron emitting cathode 5 from which an electron stream may be drawn, a control electrode 6 to control the average electron intensity connected to the usual biasing battery, and a first anode 7 maintained positive with respect to the cathode 5. The electron stream leaving the first anode 7 is accelerated, and concentrated into an electron scanning beam focused on the front surface of the mosaic electrode 2 by a second anode 8 which is preferably a conducting coating on the surface of the bulb 1 near and in the neck of the bulb but removed from that portion 25 through which is projected the optical image. The first anode 7 and the second anode 8 are maintained at the desired positive potentials, such as 300 and 1000 volts respectively with respect to the cathode 5 by a battery 9. Conventional electromagnetic deflection coils 10 are used to sweep the beam in one direction only across the target or mosaic electrode 2. In the modification shown the deflection coils are so arranged as to sweep the beam in a single plane 30 which is perpendicular to the plane of the drawing. It is obvious that conventional electrostatic deflection plates may be substituted for the single set of deflection coils if desired.

The mosaic electrode as best shown in Figure 2 35 comprises a sheet of insulating material such as a sheet of mica 11 having on one side, that is the front surface, a discontinuous photosensitive structure of line formation and on the opposite side or rear surface a continuous coating of electrically conducting material. The discon-

tinuous photosensitive structure comprises a number of closely spaced but mutually insulated and electrically isolated photosensitized metallic conductors 12, each of which extends across the mica to the opposite edge. The number of photosensitized metallic conductors depends upon the particular application of my sorting apparatus. Thus, if it is desired to sort a great number of objects simultaneously, such as might be made to flow along parallel grooves on an endless belt, the number of conductors 12 would be made equivalent to the number of grooves or objects extending crosswise of the belt. However, the number of conductors 12 may exceed the number of crosswise objects to be inspected, but in operation only a number equivalent to or a multiple of the number of crosswise objects to be inspected need be utilized. The mosaic electrode is positioned in the tube 1 in such a manner that it may have optical images of the objects to be inspected projected on its front surfaces, and also so positioned that it may be scanned by the electron beam from the electron gun which scans or sweeps across the photosensitized metallic lens such as along a path represented by the dashed line 13.

In making the mosaic electrode 2, I select a sheet of mica 11 of the desired area having a uniform thickness of approximately .002" thus obtaining a sheet of insulation sufficiently thin and of sufficiently uniform insulating properties over its exposed surface without sacrificing mechanical strength or other desired properties. The front side of the sheet of mica 11 has deposited thereon a metal such as silver which may be highly photosensitized, which metal is deposited or otherwise applied to the sheet of mica as narrow continuous rectilinear strips or conductors 12 which extend from one edge of the sheet of mica to the other edge and are of low electrical resistance throughout their length. For the inspection of a large number such as 100 of side-by-side objects, 100 of these conductors are provided, the conductors being of equal width and very closely separated one from the other. The rectilinear conductors may be applied most conveniently by printing the sheet of mica with a line cut having lines of the desired length and width, and inking with a silver containing printing vehicle, preferably finely divided silver powder, mixed to form a paste with a volatile binder, such as oil of wintergreen or oil of rosemary. As an alternative method, the multiple line type of mosaic may be formed on the sheet of mica 11 by a process somewhat similar to that disclosed by Tedham et al., in their U. S. Patent No. 2,077,442, by vaporizing the metal to be deposited and condensing the metal on the sheet of mica through a grid-like mask composed of a screen of parallel wires which cover the mica leaving parallel sections of the mica exposed so that the metal can condense thereon. During the evacuation process of the tube such volatile binders as may be present are removed and the metal lines or conductors 12 are oxidized and photosensitized such as by depositing thereon caesium or other alkali metal. A process for satisfactorily oxidizing a somewhat similar mosaic electrode is disclosed by S. F. Essig in his U. S. Patent No. 2,062,122 and a process for sensitizing a mosaic electrode in his U. S. Patent No. 2,065,570.

The next step in preparing the mosaic electrode is to deposit on the rear side of the sheet of mica opposite the side which supports the

5 individually separated metallic conductors 12, the uniform coating of metal such as platinum or other conducting material which serves as a signal plate 14 for the mosaic electrode 2.

To strengthen the thin mica sheet 11 which carries the individual metallic conductors and the electrically conductive coating such as platinum on the opposite side and which is inherently weak because of its thinness, I prefer to use a relatively thick backing sheet 15 also preferably of mica and of the same shape and area as the sheet 11. On the side of the backing sheet facing the signal plate 14 of conducting material, I provide a conductive coating 16 also preferably of metal such as platinum in good electrical contact with the platinum coating 14 to assure minimum electrical resistance between various points on the coating 14 and the external circuit which is connected through the lead 17 to a frame or clip member 18 which grips the two edges of the mica and which is in electrical contact with the signal plate through the coating 16.

Referring again to Figure 1, I provide a moving belt 20 on which the objects 21 to be inspected are arranged along parallel grooves 23, four of which are shown, it being understood that any desired number of grooves to provide a corresponding number of objects extending crosswise of the belt may be used depending upon the number of conductors 12 of the mosaic electrode 2. In accordance with my invention a narrow beam or strip of light shown by the dashed lines 24 is projected from a light source 25 through suitable lenses and a slotted or apertured mask 26 upon the objects 21 to be inspected. The objects 21 may for example be almonds which are to be selected in accordance with abrasions occurring on the skin covering. Thus assume cleaned almonds are to be selected from those from which the skin has not been entirely removed. As the objects are moved by the belt 20 under the beam of light represented at 24, images of the objects are projected upon the conductors 12 of the mosaic electrode 2 by an objective lens 27 and a pair of cylindrical lenses 28 which expand the images of the objects 21 in a direction parallel with the motion of the belt 20. It will be obvious that an image of each of the objects to be inspected will be focused upon a corresponding conductor 12 of the mosaic electrode 2 which, being photoelectrically sensitive, will lose electrons and acquire a positive charge varying in quantity in accordance with the light reflected by the objects 21. Thus, in the example considered, almonds having abrasions will produce greater electrostatic charges than those having no abrasions. Electric currents representative of the electrostatic charge on each of the conductors 12 generate signals across an output impedance 29 connected between the lead 17 and ground in a time sequence determined by the rate of scanning the conductors 12 by the electron beam. The signals are applied to an amplifier 30 of the conventional type and thence to a distributing circuit to actuate the selecting apparatus.

More particularly, and as shown in Figure 3, the output of the amplifier 30 is connected sequentially to a plurality of differential current solenoids shown schematically at 31-34 through a single segment commutator 35 mounted on a shaft 36 which is driven by a motor 37. The number of solenoids 31-34 correspond to the number of parallel tracks 23 of the belt 20 so

that one solenoid is provided for each of the objects to be inspected lying crosswise of the belt, the commutator 35 connecting each of these solenoids to the amplifier in succession. Also mounted on the motor shaft 36 and therefore operated synchronously with the commutator 35, I provide a second commutator 38 having means to provide a linear resistance characteristic around its periphery. The ends of the resistance on the commutator 38 are connected to a potential source such as the battery 39 through the conventional slip rings shown and the contactor sliding on the commutator 38 is connected to one end of the serially-connected deflection coils 10, the opposite end of which is grounded. To 15 complete the circuit I provide a source of potential such as the battery 39 connected to the slip rings and thence to the resistance commutator 8, the mid-point of the battery 39 being grounded. The resistance characteristic of the 20 commutator 38 and the potential supplied by the battery 39 are so chosen that for one complete revolution of the commutator 38 the electron beam from the electron gun is magnetically deflected across the conductors 12 of the mosaic 25 electrode 2 and is returned to its starting point. whereupon the deflection is repeated by further rotation of the commutator 38. The motor 37 also preferably drives the endless belt 20 through a suitable gear reduction mechanism. This gear reduction may be varied for the inspection of 30 different objects or of materials depending on the size of the objects or materials and the degree of inspection required. Thus the gear reducing mechanism should be constructed so that the movement of the belt 20 is relatively slow where it is wished to inspect the objects very closely, that is, for defects occurring within small distances on the objects to be inspected. If, however, objects or materials wherein the defects 35 are relatively large are to be inspected, the belt 20 may be moved at a correspondingly increased speed.

In operation, an image of each of the objects 21 is focused upon one of the conductors 12 of the mosaic electrode 2. Thus, as indicated above, if there are four side-by-side objects 21 to be inspected, four images will appear on the four or even multiple of four conductors 12 thereby developing an electrostatic charge on each of the conductors representative of the light reflecting property of the individual objects. If, however, the amount of light reflected by one of the objects 21, such as due to a difference in color or surface condition of the one object, is different from the amount of light reflected by the other objects, the electrostatic charge on the corresponding conductor will vary with respect to the charges on the other conductors. As the electron beam sweeps across the four conductors, such as along the scanning line 13, the signal impressed across the output impedance 29 and consequently on the amplifier 30 will be the same when the beam impinges upon three of the conductors, but the signal will be different when the electron beam impinges upon the remaining conductor 12. Since the electron beam is synchronized with the particular solenoid in circuit at any one time, a difference in signal due to scanning any one conductor 12 will produce a corresponding difference in energy applied to the particular differential current solenoid and, consequently, the solenoids receiving a difference in signal will cause a rejection of the particular

object or objects 21 which do not correspond to a predetermined standard.

While I have described the apparatus made in accordance with my invention with reference to a purely schematic drawing it will be apparent that my invention is by no means limited to the exact form described or to its use in the specific application referred to but that many variations may be made in the particular structure used, such as by the use of different rejectors for the solenoids and scanning and switching means of different mechanical types or of the electronic type, without departing from the scope of the invention as set forth in the appended claims.

What I claim as new is:

1. A photoelectric sorting apparatus comprising a photoelectrically sensitive tube including means to generate an electron beam, a target electrode having a plurality of elongated photosensitive charge storage elements, capacitive means associated with said charge storage elements, and means to scan said beam over said elements, a conveyor adapted to support a plurality of objects to be sorted corresponding in number to the number of said elements, a lens system between said conveyor and said target electrode to focus an elongated image of each of said objects on a corresponding charge storage element, to produce a stored electrostatic charge representative of the light received from said objects and means responsive to the stored charge on each of said charge storage elements to reject the objects from said conveyor failing to conform to a predetermined standard of light reflection from said objects.

2. A photoelectric sorting apparatus comprising an electron beam tube including means to generate an electron beam, a target electrode in the path of said beam having a plurality of elongated photosensitive charge storage elements, and a signal electrode in capacitive relation with said plurality of elements, a conveyor adapted to support a plurality of objects lying side-by-side across said conveyor and to move the objects in a direction substantially normal to the side-by-side relationship of said objects, means to focus an elongated optical image of each of said objects on a corresponding section including at least one storage element of said target, to produce electrostatic charges representative of the surface condition of said objects, a plurality of discharge means associated with said conveyor to discharge from said conveyor the objects not conforming to a predetermined standard of light reflection from said objects, means to sweep said beam in regular sequence over said charge storage elements to neutralize said electrostatic charges, and means to connect said signal electrode to each of said plurality of discharge means in a sequence determined by the sequence of sweeping said beam over said elements.

3. Apparatus as claimed in claim 2 wherein said last-mentioned means comprises a commutator to connect said signal electrode to each of said plurality of discharge means in a sequence determined by the sequence of sweeping said beam over said elements.

4. A photoelectric sorting apparatus comprising an electron discharge device including means to generate an electron beam, a target electrode in the path of said beam having a plurality of elongated photosensitive charge storage elements, and a signal electrode in capacitive relation with said plurality of elements, a conveyor adapted to support a plurality of objects

arranged in parallel rows longitudinally thereof, and to move said objects in a direction parallel with said rows, means to focus an optical image of one of said objects in each row upon a corresponding charge storage element, a plurality of means associated with said conveyor to discharge objects from each row of said objects, means to scan said electron beam over said charge storage elements, an electrical circuit including an amplifier connected between said signal electrode and said plurality of discharge means and commutating means to interrupt said circuit sequentially to all but one of said discharge means at a rate determined by the scanning of said electron beam over said charge storage elements.

5. A photoelectric sorting apparatus comprising a longitudinally movable conveyor, means to arrange objects to be sorted in parallel rows on said conveyor, a photoelectric tube associated with said conveyor, an electrode in said tube comprising a plurality of elongated photoelectrically sensitive charge storage members extending in the direction of movement of said conveyor and corresponding in number to at least the number of parallel rows of objects on said conveyor, a signal electrode in said tube capacitively associated with said plurality of charge storage members, means in said tube to generate and direct an electron beam toward said charge storage members, means to scan said beam over said storage members in a direction normal to their length, optical means between said conveyor and said tube to focus an optical image of one of the

objects in each row of objects upon a corresponding charge storage member of said tube, discharge means associated with each row of objects on said conveyor to discharge objects

5 therefrom, an amplifier connected to be energized from said signal electrode and means to sequentially connect said amplifier to each of said discharge means in a time sequence determined by the rate of scanning said electron beam over said charge storage members.

10 6. A photoelectric sorting apparatus comprising a conveyor, a plurality of side-by-side channels on said conveyor to direct objects to be sorted along a corresponding number of rows 15 on said conveyor, a photoelectric tube associated with said conveyor, an electrode in said tube comprising a plurality of charge storage members the number of said members being at least as great as the number of said channels of said 20 conveyor, a signal electrode capacitively coupled with said charge storage members, means to generate and sweep an electron beam across said charge storage members, means to project an optical image of an object in each channel of said conveyor upon a corresponding charge storage member in said tube, a magnetically operated discharge mechanism associated with each of the channels of said conveyor, and means to connect each of said discharge mechanisms with said signal electrode during the time the said 25 electron beam is being swept across a corresponding charge storage member in said tube.

30 WILLARD H. HICKOK.
